SPEAKER BAFFLE

Benjamin W. Lowell, St. Louis, Mo.

Application June 7, 1957, Serial No. 46,513

Term of patent 14 years

(Cl. D26—14)

Figure 1 is a plan view of the speaker baffle showing my new design;

Figure 2 is a view in side elevation of the speaker baffle taken from the right hand side of Figure 1; and

Figure 3 is an enlarged fragmentary sectional view of the left half of the speaker baffle taken on the line 3—3 of Figure 1.

The essential features of my design reside in the portions shown in full lines.

I claim:

The ornamental design for a speaker baffle, substantially as shown and described.
